UNITED STATES PATENT OFFICE

118,979

DESIGN FOR AN ANATOMICAL INJECTOR

Argo E. Landau, Ladue, and Wilbert F. Schaefer,
St. Louis, Mo., assignors to Royal Bond, Inc.,
St. Louis, Mo., a corporation of Missouri

Application November 4, 1939, Serial No. 88,046

Term of patent 7 years

To all whom it may concern:

Be it known that we, Argo E. Landau and Wilbert F. Schaefer, citizens of the United States, residing, respectively, at Ladue, county of St. Louis, State of Missouri, and the city of St. Louis, State of Missouri, have jointly invented a new, original, and ornamental Design for an Anatomical Injector, of which the following is a specification, reference being made to the accompanying drawings, forming a part thereof, in which:

Figure 1 is plan view with the cord plug portions omitted for convenience of illustration, Figure 2 is a side elevational view, Figure 3 is a front end view, and Figure 4 is a rear end view of an anatomical injector embodying our new design.

We claim:

The ornamental design for an anatomical injector, substantially as shown.

ARGO E. LANDAU.

WILBERT F. SCHAEFER.
